Primary Examiner — Barbara Fox(74) *Attorney, Agent, or Firm* — Sterne, Kessler, Goldstein & Fox PLLC(57) **CLAIM**

The ornamental design for a portable display device with animated graphical user interface, as shown and described.

DESCRIPTION

This application is a Continuation application of and claims priority to U.S. Design Patent application Ser. No. 29/353, 307, filed Jan. 6, 2010 and U.S. Patent application Ser. No. 29/354,643, filed Jan. 27, 2010, the disclosures of which are incorporated herein in their entirety by reference thereto.

FIG. 1 is a front view of a first image of a portable display device with animated graphical user interface showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a rear view thereof;

FIG. 8 is a top view thereof;

FIG. 9 is a left side view thereof;

FIG. 10 is a right side view thereof; and,

FIG. 11 is a bottom view thereof.

The broken lines in the drawings represent unclaimed portions of the portable display device with animated graphical user interface and form no part of the claimed design.

The appearance of the image transitions sequentially between the images shown in FIGS. 1 through 6, respectively. The process or period in which an image transitions to another forms no part of the claimed design.

Primary Examiner — Barbara Fox(74) *Attorney, Agent, or Firm* — Sterne, Kessler, Goldstein & Fox PLLC(57) **CLAIM**

The ornamental design for a portable display device with animated graphical user interface, as shown and described.

DESCRIPTION

This application is a Continuation application of and claims priority to U.S. Design Patent application Ser. No. 29/353, 307, filed Jan. 6, 2010 and U.S. Patent application Ser. No. 29/354,643, filed Jan. 27, 2010, the disclosures of which are incorporated herein in their entirety by reference thereto.

FIG. 1 is a front view of a first image of a portable display device with animated graphical user interface showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a rear view thereof;

FIG. 8 is a top view thereof;

FIG. 9 is a left side view thereof;

FIG. 10 is a right side view thereof; and,

FIG. 11 is a bottom view thereof.

The broken lines in the drawings represent unclaimed portions of the portable display device with animated graphical user interface and form no part of the claimed design.

The appearance of the image transitions sequentially between the images shown in FIGS. 1 through 6, respectively. The process or period in which an image transitions to another forms no part of the claimed design.
